UNITED STATES PATENT OFFICE.

CHARLES W. FALICK, OF BEAVER FALLS, PENNSYLVANIA.

IMPROVEMENT IN END-GATES FOR WAGONS.

Specification forming part of Letters Patent No. 126,943, dated May 21, 1872.

Be it known that I, CHARLES W. FALICK, of Beaver Falls, Beaver county, Pennsylvania, have invented a new and useful Improvement in End-Gates for Wagons, of which the following is a full description, reference being had to the accompanying drawing, in which—

Figure 1 is an end view of the end-gates and attachments when the gates are closed. Fig. 2 is a perspective view of the same. Fig. 3 is an end view of the gates and attachments when the fastening-bars are disengaged from the hooks. Fig. 4 is perspective view of the same, the gates being partly open.

The invention consists in end-gates and hinges and fastenings thereto for opening and closing the hind end of wagon-beds, being so constructed, applied, and arranged that the gates may be easily closed and securely fastened, readily unfastening, and speedily opened, and without difficulty altogether removed from the wagon.

H represents the main portion of the end-gates, to the heels of which are secured suitably the plates L bearing the hinge-eyes E, which rest upon the hinge-supports F, that are firmly secured in the side of the wagon-bed. The upper hinges are secured by screw-plugs a, which being withdrawn the gates may be raised and lifted off when not required. The screw-plugs are attached to a chain fastened to the side of the wagon-bed to prevent loss. The plates b, d, f, and m are firmly secured upon the main portions of the gates, as shown. Through the plate b the downwardly-turned hooks c are fastened, and through the plates d and m the upwardly-turned hooks c' are fixed. To the plates d are pivoted the fastening-bars A having hooks p and q at their ends, and the notches s, near the pivots, adapted, as shown, to engage in the hooks c and c' to fasten the gates securely when closed. The

bars are prevented from becoming unhooked by the pin or key t, which is inserted in a hole or slot through the plate m and just above the hook q when in place. The pin is fastened to the gate by a chain, D, to prevent loss.

These hooks and bars are adapted to secure strength to the wagon-bed, by tending to prevent the sides from spreading when the wagon is loaded, and also to prevent the gates from being forced open under the same circumstances.

The gates are easily and quickly opened by removing the pin t, disengaging the bars A, and first opening the left-hand gate, and they are as easily and quickly closed by a reverse operation; they may be removed readily also from the wagon-bed by taking out the screw-plug a from the hinge.

I claim as my invention—

1. The combination of the pivoted bars A, having hooks p and q, and with or without the notches s, the hooks c and c', the pin or key t, and the gates H, all constructed and arranged substantially as and for the purposes set forth.

2. The combination of the plates L bearing the hinge-eyes E, the hinge-support F attached to the side of the wagon-bed, the screw-plug a fitted to the hinge-eye, and the gates H, all constructed and arranged substantially as and for the purposes set forth.

3. End-gates for wagon-beds, consisting of the gates H, the bars A, the hooks c and c', the hinge-eyes E, the hinge-supports F, and the screw-plug a, all constructed, arranged, and applied substantially as and for the purposes set forth.

CHARLES WM. FALICK.
